UNITED STATES PATENT OFFICE.

EDWARD A. FIELD AND EDWARD A. FIELD, JR., OF CHICAGO, ILLINOIS, ASSIGNEES
TO FIELD ENGINEERING COMPANY, OF CHICAGO, ILLINOIS.

VALVE-CONTROL MECHANISM.

Application filed November 23, 1925. Serial No. 70,960.

Our improved valve control mechanism is especially designed by us for use in connection with fuel burners of the type shown in our application for Letters Patent filed 5 April 20, 1925, Serial No. 24,422, although adapted for use in various relations where it is desired to automatically close a valve in the event of a surplus of liquid having been delivered and not consumed as in normal operation.

The main object of this invention is to provide an improved valve control mechanism which is very efficient and positive in its operation.

15 A further object is to provide an improved valve control mechanism which is not likely to get out of order and is very durable in use and also one which may be quickly reset by an unskilled person.

20 Objects pertaining to details and economies of construction and operation of our invention will definitely appear from the detailed description to follow. The invention is clearly defined and pointed out in the 25 claims.

A structure embodying the features of our invention is illustrated in the accompanying drawing forming a part of this application, in which:

30 Fig. I is a side elevation of our improved control mechanism, portions of a furnace and burner and a supply tank being conventionally shown in operative relation to the control mechanism.

35 Fig. II is a detail view mainly in vertical section through the control mechanism on a line corresponding to line 2—2 of Fig. III.

Fig. III is a detail view mainly in section on a line corresponding to broken line 3—3 40 of Fig. II.

Fig. IV is a detail view of certain of the operating parts removed from the housing for convenience in illustration.

45 Fig. V is a detail side view of the parts shown in Fig. IV, the counterweight being shown by full lines in set position and by dotted lines in actuated position.

Fig. VI is an enlarged detail section on a line corresponding to line 6—6 of Figs. IV 50 and VII.

Fig. VII is an enlarged detail view par-

tially in section on a line corresponding to broken line 7—7 of Fig. VI.

Fig. VIII is a detail horizontal section on a line corresponding to line 8—8 of Fig. III. 55

Fig. IX is a perspective view with the housing cover open and with the parts in resetting position.

In the drawing similar numerals of reference indicate similar parts in all the views 60 and the sectional views are taken looking in the direction of the little arrows at the ends of the section lines.

Referring to the drawing, 1 represents the fire pot of a furnace, 2 a liquid fuel burner 65 and 3 the fuel supply tank. These parts are shown in order to illustrate the relation of our valve control mechanism thereto.

Our improved valve control mechanism comprises a housing 4 open at the bottom, a 70 receptacle 5 being pivotally mounted at 6 within the housing and constituting the bottom thereof. This receptacle has a discharge lip or spout 7 at one edge. The housing has an opening 8 therein provided with a 75 cover 9 pivoted at 10, the purpose of this being to afford access to the interior of the housing. The housing has another opening 11 therein in which is seated an annular member 12 provided with bracket arms 13 80 projecting into the housing to a central point.

A valve casing 14 is seated upon this member 12 and has an inlet chamber 15 connected to the supply tank by the pipe 16 and a discharge chamber 17 connected to the burner by the pipe 18. These chambers are connected by a port 19 terminating in a valve seat 20.

The chamber 15 is closed at one end by 85 a clean-out plug 21 carrying a tubular screen 22 into which the fuel flows from the pipe 16 so that the screen can be readily removed for cleaning as occasion requires.

The valve 23 is of the needle type and has 90 a diaphragm 24 secured to its stem 25 and clamped in a seat 26 provided therefor in the annular member 12. This diaphragm constitutes the inner wall for the outlet chamber of the valve casing and avoids the 100 use of a packing for the valve stem.

A yoke-like actuating lever 27 is mounted

on pivots 28 carried by the arms 13, the overflow bucket 29 being suspended from this lever by the links 30. The links are carried by the pivots 31 on the lever which are disposed so that the pivots 28 for the lever constitute stops for the links. The bucket is suspended within the receptacle 5 as shown in Fig. II.

The lever 27 has an arm 32 with an upwardly projecting stop portion 33. This arm 32 is connected by the link 34 to the valve stem, the link comprising a section 35 pivoted at 36 to the valve stem, a section 37 pivoted at 38 to the lever arm 32 and a threaded section 39 connecting the sections 35 and 37. The pivot 38 is disposed out of alinement with the pivots 28 so that an eccentric action for the link to the actuating lever is provided.

We provide a weight 40 having a yoke arm 41 mounted on the pivots 28 for the actuating lever. When the parts are in set position this weight rests on the stop 33 on the arm 32. The over-flow pipe 42 leads from the burner to the spout 43 within the housing arranged to deliver to the bucket so that upon the burner becoming inoperative through extinguishing the flame or a surplus of fuel accumulating for any reason, it returns to the bucket and actuates the lever 27 to close the valve. The weight swinging past the pivot center imparts a blow to the lever and insures the seating of the valve.

When it is desired to reset the parts it is only necessary to tilt the receptacle 5 on its pivot to the position indicated in Fig. IX, which discharges the bucket, the contents being discharged from the receptacle 5 into a pan or other receptacle placed beneath the same. The finger 44 on the receptacle engages the weight at the same time and swings it to set position against the stop 33.

To regulate the normal flow of fuel, we provide a stop member 45 which is pivoted at 46 to project through the yoke member 35 of the link engaging the end of the valve stem. An adjusting screw 47 is provided having a concealed end so that it is adjusted by the person setting the burner.

To provide for adjustment by the operator, we provide a second adjusting screw 48 which is threaded into the member 12 and provided with a hand wheel 51 having a stop 52 thereon. The coacting adjustable stop 53 has a sleeve-like portion 49 embracing the screw and seated in the member 12. A set screw 50 secures this stop 53 in its adjusted positions. This stop 53 also constitutes an index member for the hand wheel.

With this arrangement of parts we provide a mechanism which is very positive in its action and one which is very easily reset as occasion requires.

We have not attempted to illustrate cer-

tain modifications and adaptations which we contemplate as we believe the disclosure made will enable those skilled in the art to embody or adapt our improvements as may be desired.

Having thus described our invention what we claim as new and desire to secure by Letters Patent is:

1. In a structure of the class described, the combination of a housing open at the bottom, a receptacle pivotally mounted within and constituting a bottom for the housing, a valve casing mounted on said housing and provided with inlet and discharge chambers, there being a port connecting said chambers, a valve coacting with said port, said valve being provided with a stem having a diaphragm secured thereto and constituting a wall for said discharge chamber, an overflow bucket within said housing, spaced bracket arms projecting centrally into said housing, a yoke-like lever pivotally mounted on said bracket arms and provided with an arm disposed between said bracket arms, a link connecting said arm on said lever to said valve stem, the pivot for the link to said arm being eccentric relative to the pivots for said lever, suspending links for said bucket pivotally mounted on said lever, the pivots for said lever constituting stops with which the suspending links engage when the parts are in set position, a tapet weight having a forked arm pivotally mounted on the pivots for said lever to strike said lever when actuated and to engage its said arm when the parts are in set position, and a bucket dumping member on said receptacle engaging the bucket to tilt the same when the receptacle is tilted, said receptacle being provided with a weight returning finger whereby the bucket is discharged and the parts are returned to set position upon the tilting of the receptacle.

2. In a structure of the class described, the combination of a housing open at the bottom, a receptacle pivotally mounted within and constituting a bottom for the housing, a valve casing mounted on said housing and provided with inlet and discharge chambers, there being a port connecting said chambers, a valve coacting with said port, said valve being provided with a stem having a diaphragm secured thereto and constituting a wall for said discharge chamber, an overflow bucket within said housing, spaced bracket arms projecting centrally into said housing, a yoke-like lever pivotally mounted on said bracket arms and provided with an arm disposed between said bracket arms, a link connecting said arm on said lever to said valve stem, the pivot for the link to said arm being eccentric relative to the pivots for said lever, and suspending links for said bucket pivotally mounted on said lever, the pivots for said lever constituting stops

with which the suspending links engage when the parts are in set position.

3. In a structure of the class described, the combination of a housing open at the bottom, 5 a receptacle pivotally mounted within and constituting a bottom for the housing, a valve casing mounted on said housing and provided with inlet and discharge chambers, there being a port connecting said chambers, 10 a valve coating with said port, said valve being provided with a stem having a dia- phragm secured thereto and constituting a wall for said discharge chamber, an over- flow bucket within said housing, a pivotally 15 mounted lever, a link eccentrically connected to said lever and pivotally connected to said valve stem, a suspending link for said bucket pivotally mounted on said lever, a pivotally mounted weight adapted to engage said lever 20 when the parts are actuated and to be sup- ported thereby when the parts are in set po- sition, and a bucket dumping member on 25 said receptacle engaging the bucket to tilt the same when the receptacle is tilted, said receptacle being provided with a weight en- gaging finger whereby the bucket is dis- charged and the parts are returned to set po- sition upon the tilting of the receptacle.

4. In a structure of the class described, the combination of a housing open at the bottom, a receptacle pivotally mounted within and constituting a bottom for the housing, a valve casing mounted on said housing and provided with inlet and discharge chambers, 30 there being a port connecting said chambers, a valve coating with said port, said valve being provided with a stem having a dia- phragm secured thereto and constituting a wall for said discharge chamber, an over- flow bucket within said housing, a pivotally 35 mounted lever on which said bucket is mounted operatively connected to said valve stem, a pivotally mounted weight adapted to strike said lever when the parts are actuated, and a bucket dumping member on said 40 receptacle engaging the bucket to tilt the same when the receptacle is tilted, said re- ceptacle being provided with a weight re- turning finger on said receptacle whereby 45 the parts are returned to set position upon the tilting of the receptacle to discharge the bucket.

5. In a structure of the class described, the combination of a valve, a receptacle mounted 50 for tilting movement, an overflow bucket within said receptacle, a pivotally mounted yoke-like lever provided with an arm, an adjust- able link connecting said arm on said lever to said valve, the pivot connection for 55 the link to said arm being out of alinement with the pivots for said lever, suspending links for said bucket pivotally mounted on said lever, the pivots for said lever constituting stops with which the suspending links 60 engage when the parts are in set position, a

weight pivotally mounted on the pivots for said lever to strike said arm when the parts are actuated, and a bucket dumping member on said receptacle adapted to engage the bucket to tilt the same when the receptacle 70 is tilted, said receptacle being provided with a weight returning member whereby the parts are returned to set position upon the tilting of the receptacle to discharge the 75 bucket.

6. In a structure of the class described, the combination of a valve, an overflow bucket, 80 a pivotally mounted yoke-like lever provided with an arm, an adjustable link connecting said arm on said lever to said valve, the pivot connection for the link to said arm being out of alinement with the pivots for said lever, and suspending links for said bucket pivotally mounted on said lever, the 85 pivots for said lever constituting stops with which the suspending links engage when the parts are in set position.

7. In a structure of the class described, the combination of a housing open at the bottom, a receptacle pivotally mounted within and constituting a bottom for the housing, 90 a feed valve, an overflow bucket within said housing, a pivotally mounted lever provided with an arm, a link connecting said arm to said valve, the pivot connection for the link to said arm being out of alinement with the pivot for said lever, a suspending link for said bucket pivotally mounted on said lever, there being a stop engaging said suspending link when the parts are in set position, a pivotally mounted weight engaging said arm on said yoke when the parts are in set position and adapted to strike said lever when actuated, a bucket dumping member on said receptacle 100 engaging the bucket to tilt the same when the receptacle is tilted, said receptacle being provided with a weight engaging member whereby the parts are returned to set position upon the tilting of the receptacle to discharge the bucket, and an adjustable stop 105 means for said valve.

8. In a structure of the class described, the combination of a feed valve, an overflow bucket, a pivotally mounted lever provided with an arm, an adjustable link connecting said arm to said valve, the pivot connection for the link to said arm being out of alinement with the pivot for said lever, a suspending link for said bucket pivotally mounted on said lever, there being a stop 110 engaging said suspending link when the parts are in set position, and a pivotally mounted weight adapted to strike said lever when the parts are actuated.

9. In a structure of the class described, the combination of a feed valve, an overflow bucket, a pivotally mounted lever provided with an arm, an adjustable link connecting said arm to said valve, the pivot connection 115 for the link to said arm being out of aline- 120

ment with the pivot for said lever, and a suspending link for said bucket pivotally mounted on said lever, there being a stop engaging said suspending link when the parts are in set position.

10. In a structure of the class described, the combination of a feed valve, an overflow bucket, a pivotally mounted lever provided with an arm, a link connecting said arm to said valve, the pivot connection for the link to said arm being out of alinement with the pivot for said lever, and a suspending link for said bucket pivotally mounted on said lever, there being a stop engaging said suspending link when the parts are in set position.

11. In a structure of the class described, the combination of a valve, an overflow bucket, an actuating lever from which said bucket is suspended, a toggle connection for said bucket to said valve stem, a pivotally mounted counterweight adapted to engage said lever when the parts are in set position, a pivoted valve and adjusting member co-acting with said valve stem, a pair of adjusting screws for said valve adjusting member, one of which is provided with a hand wheel having gaging indicia thereon, and a coacting adjustably mounted stop providing an index member for such indicia.

12. In a structure of the class described, the combination of a valve, an overflow bucket, an actuating lever from which said bucket is suspended, a toggle connection for said bucket to said valve stem, and a pivotally mounted counterweight adapted to engage said lever when the parts are in set position.

13. In a structure of the class described, the combination of a housing open at the bottom, a receptacle pivotally mounted within and constituting a bottom for said housing, a valve casing mounted on said

housing, a feed valve, a pivotally mounted actuating lever, an overflow bucket suspended therefrom within said receptacle, an operating connection for said actuating lever to said valve, a pivotally mounted weight acting on said lever when the parts are actuated, and a bucket dumping member on said receptacle engaging the bucket to tilt the same when the receptacle is tilted, said receptacle being provided with a weight engaging part whereby the parts are returned to set position upon the tilting of the receptacle and the bucket discharged.

14. In a structure of the class described, the combination of a feed valve, an overflow bucket, an actuating lever upon which said bucket is mounted, a counterweight operatively associated with said actuating member, an adjustable link eccentrically connected to said actuating lever and pivotally connected to said valve, and a manually adjusted stop means for limiting the opening of the feed valve.

15. In a structure of the class described, the combination of a feed valve, an overflow bucket, an actuating lever upon which said bucket is mounted, a counterweight operatively associated with said actuating member, and a link eccentrically connected to said actuating lever and pivotally connected to said valve.

16. In a structure of the class described, the combination of a feed valve, a pivotally mounted actuating lever, an overflow bucket suspended therefrom within said receptacle, a toggle connection for said actuating lever to said valve, and a pivotally mounted counterweight acting on said lever when the parts are in set position.

In witness whereof we have hereunto set our hands.

EDWARD A. FIELD.

EDWARD A. FIELD, JR.
